Primary Examiner — Rosemary K Tarca*Assistant Examiner* — Nathaniel D. Buckner(74) *Attorney, Agent, or Firm* — Banner & Witcoff, Ltd.(57) **CLAIM**

The ornamental design for a charger, as shown and described.

DESCRIPTION

FIG. 1 is a front perspective view of a charger showing our new design;

FIG. 2 is a rear perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The uneven-length broken lines in FIGS. 1-8 immediately adjacent to the shaded area represents the bounds of the claimed design. The even-length broken line showing of the remainder of the charger in FIGS. 1-8 is for environmental purposes only and forms no part of the claimed design.

1 Claim, 6 Drawing Sheets(56)
